(57) **CLAIM**

The ornamental design for a pair of slippers, as shown and described.

DESCRIPTION

FIG. 1 is a top, heel end, perspective view of a pair of slippers, showing our new design embodied in the right foot slipper thereof.

FIG. 2 is a right side plan view of the slipper of FIG. 1.

FIG. 3 is left side plan view of the slipper of FIG. 1.

FIG. 4 is a top plan view of the slipper of FIG. 1.

FIG. 5 is a bottom plan view of the slipper of FIG. 1; no claim being made to the appearance of the slipper sole bottom surface.

FIG. 6 is toe end elevational view of the slipper of FIG. 1; and, FIG. 7 is a heel end elevational view of the slipper of FIG. 1. The corresponding left foot slipper is a mirror image of the right foot slipper as shown in FIGS. 1-7.

The broken lines shown on the slipper represent stitching and form part of the claim.
